UNITED STATES PATENT OFFICE.

OSCAR W. MOORE, OF CHICAGO, ILLINOIS.

TEMPERATURE INDICATOR.

Application filed September 21, 1921. Serial No. 502,099.

To all whom it may concern:

Be it known that I, OSCAR W. MOORE, a citizen of the United States of America, and a resident of Chicago, county of Cook, and 5 State of Illinois, have invented certain new and useful Improvements in Temperature Indicators, of which the following is a specification.

This invention relates to temperature indicators designed with particular reference to the requirements of automobiles in indicating the temperature of the cooling medium in the radiator.

The objects of the invention are to provide a disk-shaped indicator which may be screwed into the cap for covering the filling aperture in the radiator, and which will permanently indicate or signal the temperature conditions of the engine indirectly by being subject to the action of the cooling fluid in the radiator. It is also the purpose of the invention to provide improvements in the operating mechanism of such indicators, and to provide an improved 25 multiple unit expansion motor for operating this mechanism.

The objects of the invention may be accomplished by the device illustrated in the drawings, in which—

30 Fig. 1 is an exterior view of one face of the instrument, the front and rear being similar in appearance.

Fig. 2 is a sectional view on the line 2—2 of Fig. 1.

35 Fig. 3 is a sectional view taken on the line 3—3 of Fig. 2.

Fig. 4 is an enlarged detail of the expansion motor.

The construction shown is designed to 40 avoid the use of indicating hands and dials which are difficult to read and, therefore, provision is made for signalling at sight openings passing through the device by means of colored disks, such as red or green. These disks are movable to more or less cover the sight openings, and are moved by temperature actuated mechanism to indicate part green and part red at the sight openings when the temperature is normal.

45 Green alone at one sight opening indicates that the water in the radiator is cool, while red alone at the remaining sight opening indicates that the temperature is dangerously high. These colored disks are at the 50 ends of a lever which is shifted more or less around a central pivot by means of a link

connection to an expansion motor, shown in the drawings as a plurality of U-shaped thermostatic laminae, one bearing against the other to produce a multiple effect upon expansion.

Referring to the drawings, the device is shown as having a casing in the form of a ring 1, having a depending boss 2, within which is threaded a cylindrical depending container 3 for the expansion unit 4. This unit is shown as consisting of a plurality of U-shaped thermostatic laminae 5 bearing against each other, and each provided with apertures 6 and 7, through which pass the 65 rods 8 and 9. The rod 9 is riveted to the lower arm of the bottom U-strip while being free from the remaining U-strips. This rod bears against a collar 10 supported at the lower end of rod 8, and therefore serves 70 to shift the rod 8 downwardly upon expansion of the U-shaped elements 5. The rod 8 at its upper end is pivotally connected to a link 11 which serves to transmit motion from the rod to the semaphore lever 12. 75 The point of connection 13 between link 11 and lever 12 is close to fulcrum 14 of the lever so as to make this lever sensitive to slight movements of the expansion motor. The expansion of the motor is resisted by a light spring 15, which serves 80 to steady the action of the mechanism. The lever 12 carries a green disk 16 at one end and a red disk 17 at the other end, for respectively passing in front of the sight 85 openings 18 and 19, cut in both the front and rear disk-shaped plates 20 and 21, which with the casing 1 serve to enclose the lever 12 and its connected parts. The plates 20 and 21 are faced by glass disks 22.

In installing the device, the cap for the filling aperture of the radiator is drilled and threaded to receive the thermometer by engagement therewith at the threaded part 100 23 at the upper end of the casing 3 for the expansion motor. This casing extends downwardly into the radiator so as to receive heat therefrom and communicate it to the expansion motor.

In the operation of the device, the U-shaped thermostatic elements expand or contract according to temperature changes, and their combined movement is communicated through rod 9 to the collar 10 on the lower end of rod 8. Upon expansion, the 105 rod 8 is lowered, rocking the green disk 16 more or less away from the sight opening

18 and bring the red disk 17 a corresponding amount into view at the sight opening 19. When the thermostatic motor contracts the spring 15 is permitted to restore the 5 green disk to the sight opening.

Although but one specific embodiment of this invention has been herein shown and described it will be understood that numerous details of the construction shown may 10 be altered or omitted without departing from the spirit of this invention as defined by the following claim.

I claim:

15 A temperature indicator of the class described, comprising an annular casing having axially spaced face plates supported therein, said face plates being each provided with a pair of circular sight openings

spaced outwardly from the axis of the casing, a semaphore pivotally supported between said face plates at the axis of the casing and extending outwardly at opposite sides of its pivotal support, and at each end being provided with a colored disk for display at said sight openings, and thermostatic means supported by said casing for actuating said semaphore, whereby the colored disks on the ends of the semaphore will move more or less into or out of registration with said sight openings and thereby giving indication of temperature by the size of the unobstructed crescent-shaped space remaining at the sight openings.

Signed at Chicago this 17 day of Sept. 1921.

OSCAR W. MOORE.
